UNITED STATES PATENT OFFICE.

ARTHUR M. ROSE, OF YONKERS, NEW YORK, ASSIGNOR TO THE LOWELL
MANUFACTURING COMPANY, OF MASSACHUSETTS.

DESIGN FOR CARPET.

SPECIFICATION forming part of Design No. 27,555, dated August 17, 1897.

Application filed February 4, 1897. Serial No. 622,053. Term of patent 3½ years.

To all whom it may concern:

Be it known that I, ARTHUR MIDDLETON ROSE, a citizen of the United States, and a resident of Yonkers, in the county of Westchester and State of New York, have invented 5 a new and original Design for Carpets and Borders, of which the following is a specification.

This invention comprises two parts—namely, the design A for a carpet and the design B for a border; and I do hereby declare that the drawing accompanying this specification conveys to any one a clear understanding of the same and is sufficient to enable such person to use my invention. 15

The body A is characterized by separated figures connected by festoons of stem and flower forms.

The border B is characterized by a series 20 of stripes b' b^2 b^3 b^4 b^5 , &c., the stripes of the series being each of substantially uniform

shade from edge to edge and the series growing gradually darker from the inner to the outer stripe. It is also characterized by separated slender figures connected by lines of 25 stem and flower forms.

What I claim as new, and desire to secure by Design Letters Patent, is—

1. In the design for a carpet, the body A, substantially as shown. 30
2. In the design for a carpet, the border B, substantially as shown.
3. The design for a carpet consisting of the body A and the border B, substantially as shown. 35

In testimony whereof I have signed my name to this specification in the presence of two subscribing witnesses.

ARTHUR M. ROSE.
